US00D499035S

(12) **United States Design Patent** (10) Patent No.: **US D499,035 S**
Cook et al. (45) Date of Patent: **** Nov. 30, 2004**

(54) **DETECTION APPARATUS**

(75) Inventors: **Richard Cook**, Derwood, MD (US); **Charles Quentin Davis**, Frederick, MD (US); **David Robert DeLallo**, Olney, MD (US); **Pankaj Oberoi**, Rockville, MD (US); **Hans Biebuyck**, Rockville, MD (US); **Rober Krikor Matikyan**, Rockville, MD (US); **Neil S. Rothman**, Baltimore, MD (US); **Christopher W. Glupker**, Van Nuys, CA (US); **Lance Hussey**, Simi Valley, CA (US); **Ravi K. Sawhney**, Calabasas, CA (US)

(73) Assignee: **BioVeris Corporation**, Gaithersburg, MD (US)

(**) Term: **14 Years**

(21) Appl. No.: **29/180,894**

(22) Filed: **May 1, 2003**

(51) LOC (7) Cl. **10-04**

(52) U.S. Cl. **D10/81**; D24/234

(58) Field of Search D10/81; D24/186, D24/234; 422/104, 56, 58, 61, 102, 43, 46, 48, 100, 63-68

(57) **CLAIM**

The ornamental design for a detection apparatus, as shown and described.

DESCRIPTION

FIG. 1 is a front perspective view showing the new design; FIG. 2 is a front elevation view thereof;

FIG. 3 is a rear elevation view thereof;

FIG. 4 is a side elevation view thereof, the side opposite that shown in FIG. 4 being the mirror image thereof; and,

FIG. 5 is a top plan view thereof.

No bottom plan view is provided since the bottom is unadorned.

The portions of the drawings in dashed lines form no part of the claimed invention.
